(57) **CLAIM**

The ornamental design for a vehicle roof rack, as shown and described.

DESCRIPTION

FIG. 1 is a perspective view of a vehicle roof rack, showing my new design;

FIG. 2 is a perspective bottom view thereof;

FIG. 3 is a front view thereof;

FIG. 4 is a back view thereof;

FIG. 5 is a left side view thereof, the right side view being identical thereto;

FIG. 6 is a top view thereof; and,

FIG. 7 is a bottom view thereof.

The broken lines in the drawings represent unclaimed subject matter and form no part of the claimed design.
